UNITED STATES PATENT OFFICE.

FRANKLIN G. BURLEY, OF BOSTON, MASSACHUSETTS.

CYLINDER FOR COMPOUND STEAM-ENGINES.

SPECIFICATION forming part of Letters Patent No. 655,685, dated August 14, 1900.

Application filed October 23, 1899. Serial No. 734,429. (No model.)

To all whom it may concern:

Be it known that I, FRANKLIN G. BURLEY, a citizen of the United States, residing in Boston, in the county of Suffolk and State of Massachusetts, have invented new and useful Improvements in Cylinders for Double and Compound Steam-Engines, of which the following is a specification.

In this invention the effect of two cylinders is produced by a single cylinder divided longitudinally and vertically into equal halves, said halves being separated by a partition which closes each half. The pistons are constructed with wedges for packing adapted to the changed conditions and to the shape of the half-cylinders.

The invention is primarily intended for double engines; but it is equally applicable to compound engines.

The nature of the invention is fully described in detail below and illustrated in the accompanying drawings, in which—

Figure 1 is a plan view of my improved cylinder as adapted for a double steam-engine. Fig. 2 is a horizontal section of the same, showing one of the pistons in plan. Fig. 3 is a cross vertical section taken on line X, Fig. 2. Fig. 4 is a cross vertical section illustrating my improved cylinder as adapted for a compound engine.

Similar letters of reference indicate corresponding parts.

In Figs. 1, 2, and 3, A A represent two complete or full halves of a cylinder, such as would be produced by dividing a cylinder longitudinally and vertically into two equal parts. These two parts A are separated by a partition B, which is placed between them, forcing them a short distance apart. The parts A and partition B are secured together by bolts C through flanges A'. D D represent pistons, and E piston-rods, extending through suitable packing in the head or end a, which is preferably a single integral plate extending across both cylinders or half-cylinders. The plate a' at the opposite end may be similarly constructed. The pistons conform in shape to the half-cylinders, and each is provided with wedges F for packing, extending from the interior of the piston out oppositely against the flat and concave inner surfaces of the cylinder. Each wedge is secured to a plate or bar F', the two bars being held apart

by suitable springs H on rods I, extending from one plate through suitable openings in the other. Thus the wedges are held normally against the opposite sides of the cylinder for packing purposes. H H are the valve-boxes, H' the steam-inlets thereto, I I the valve-rods, J J the steam-inlets to the divided cylinder, and K K the exhaust-ports, all constructed as usual. Thus a double cylinder is provided in substantially the space which would be occupied by a single cylinder, and economy of space and material is produced without impairing the efficiency of the engine.

In Fig. 4, L L' represent the two parts of the divided cylinder separated by the partition M, such cylinder being intended for a compound steam-engine. N represents the steam-chest on the high-pressure side, and N' the steam-chest on the low-pressure side. P P are the ordinary D-valves. R is the steam-inlet on the high-pressure side, and S is the pipe which takes the steam from the exhaust in the steam-chest N on the high-pressure side to the steam-chest N' on the low-pressure side. The arrangement of the steam-chests, valves, and pipe L is not new in this invention, but is illustrated as applied to the divided cylinder.

Having thus fully described my invention, what I claim, and desire to secure by Letters Patent, is—

1. In a steam-engine, a double cylinder comprising a pair of cylinders, each consisting of a half-cylinder such as would be produced by dividing a cylinder longitudinally and vertically into two parts; a partition separating the two said cylinders or part cylinders; means for securing the open sides of the two said cylinders to the partition on the opposite sides thereof; steam-chests; distributing-valves; and exhaust and inlet ports, substantially as described.

2. In a steam-engine, a pair of semicylindrical cylinders; a dividing plate or partition, said semicylindrical cylinders having their open sides facing and secured to opposite sides of said dividing-plate; steam-chests; distributing-valves; and exhaust and inlet ports, substantially as set forth.

FRANKLIN G. BURLEY.
